(57) **CLAIM**

The ornamental design for a cornhole board cover, as shown and described.

DESCRIPTION

FIG. 1 is a front perspective view of the cornhole board cover, showing the new design in an environment of use; FIG. 2 is a front perspective view of the cornhole board cover with environment removed for clarity of disclosure. FIG. 3 is a front elevational view of the cornhole board cover thereof;

FIG. 4 is a rear elevational view of the cornhole board cover thereof;

FIG. 5 is a left side elevational view of the cornhole board cover thereof;

FIG. 6 is a right side elevational view of the cornhole board cover thereof;

FIG. 7 is a top plan view of the cornhole board cover thereof;

FIG. 8 is a bottom plan view of the cornhole board cover thereof;

FIG. 9 is a rear perspective view of the cornhole board cover thereof; and,

FIG. 10 is an exploded perspective view of the cornhole board cover thereof.

The broken lines illustrate environmental subject matter only and forms no part of the claimed design.
